CORROSION PROOF TERMINAL FOR ALUMINUM WIRE CONDUCTOR

Ronald Clarence Hoffman, 414 Elizabeth St.,
Williamstown, Pa. 17098

Filed Nov. 17, 1970, Ser. No. 26,738

Term of patent 14 years

Int. Cl. D13—03

U.S. Cl. D26—1 A

FIG. 1 is a front elevation of a corrosion proof terminal for aluminum wire conductor showing my new design;

FIG. 2 is a top plan view thereof;

FIG. 3 is a side elevation thereof;

FIG. 4 is a bottom plan view thereof; and

FIG. 5 is a perspective view thereof.

The broken line showing of a conductor fragment in FIGS. 1 through 4 is for illustrative purposes only.

I claim:

The ornamental design for a corrosion proof terminal for aluminum wire conductor, as shown.
